UNITED STATES PATENT OFFICE.

URBAN A. WOODBURY, OF BURLINGTON, VERMONT.

AUTOMATIC RAILWAY-SWITCH.

SPECIFICATION forming part of Letters Patent No. 758,401, dated April 26, 1904.

Application filed October 22, 1903. Serial No. 178,007. (No model.)

To all whom it may concern:

Be it known that I, URBAN A. WOODBURY, a citizen of the United States, residing at Burlington, in the county of Chittenden and State 5 of Vermont, have invented new and useful Improvements in Automatic Railway-Switches, of which the following is a specification.

My invention relates to railway-switches of the type known as "automatic safety," in 10 which means are provided whereby in case the switch has been inadvertently left open it will be closed by a train on the main track approaching the switch from the front side thereof.

15 One object of my invention is to provide automatic mechanism for the purpose described which will not interfere with or affect the ordinary operation of switching, but which will always be ready to operate and which 20 will not have complicated parts to get out of order or be affected by climatic conditions.

Another object of my invention is to so construct and arrange the mechanism that the switch can yield as usual when it has been 25 inadvertently set wrong and a train passes through it from the heel or rear side thereof and so that in so yielding the automatic mechanism will be set in operation to throw the switch as soon as the first pair of wheels 30 forces the rails over. When, however, the switch is set for the main line and a train passes off from the siding onto the main line, I prefer to construct the mechanism so that the switch-rails can yield without setting off. 35 The automatic mechanism, so that the switch will remain closed to the main line.

Another object of my invention is to provide a trip device arranged to be operated by means carried on the locomotive and which 40 can be absolutely relied upon to release the automatic mechanism promptly if the switch has been left open, this result being attained by causing the trip to strike a device which normally maintains a spring energized, thus 45 obviating the necessity of overcoming the inertia of and setting in motion a number of connected parts.

Another object of my invention is to so connect the trip with the switch-rod that the

former will be automatically moved into in- 50 operative position when the switch is closed to the main line.

Another object of my invention is to provide means on the locomotive to coöperate with the trip, which means can be removed 55 from operative position by the engineer when the switch is opened and it is desired to run onto the siding.

Further objects and advantages of my invention will more fully appear hereinafter, 60 and the various mechanisms and combinations whereby the objects and advantages are attained will be pointed out in the annexed claims.

Referring now to the accompanying drawings, in which like numerals are used to represent the same parts in the different views, Figure 1 is a plan view showing the tracks and one form of my invention, part thereof being shown in section. Fig. 2 is a side elevation of the trip device. Fig. 3 is an end elevation of the same. Fig. 4 shows in side elevation, and Fig. 5 in end elevation, the extra wheel on the locomotive to coöperate with the trip. Fig. 6 is an end view of the 75 cylinder.

In the figures, 1 represents the rails of the main track, and 2 and 3 the switch-rails carried by the switch-rod 5. This rod terminates in a head 6, slidably mounted in a cylinder 7, having heads 8 and 9, through the former of which said switch-rod can slide. The cylinder itself can move longitudinally, it being preferably supported on a roller 10 and guided by another roller 11 for that purpose. Said roller 11 is arranged at the side of the cylinder, so as to resist the tendency of the trip-rod, to be hereinafter described, to pull the cylinder over laterally. A coil-spring 12 is placed between the head 6 and the head 90 8 of the cylinder, which spring tends to force the rod 5 within the cylinder. The rod 5 is provided with a stop consisting of a head or washer 13, pinned or otherwise secured thereto to limit its outward movement from the 95 cylinder. The rod 5 carries outside of the cylinder a pin or lug 14 and in the form shown in these views a pivoted dog 15. The

cylinder-head 8 is provided with a bracket 16, on which are pivoted a lever 17, which is adapted to engage the pin or lug 14 on the side thereof nearest the cylinder, and a latch 18 in the form of a bell-crank lever, the short arm of which is adapted to engage the nose of the latch 17 and the long arm of which is adapted to engage the side of the dog 15, as shown. To this dog is pivoted one end of the trip-rod 19, which extends alongside one of the rails of the main track, being supported in any suitable way, and carries at its other end a lug 20, having lateral projections 21. To the side of the rail adjacent to the end of said trip-rod is firmly attached a bracket 22, having therein a slot 23, open at its lower end. The trip-rod is adapted to be inserted within this slot and to be held against longitudinal movement by the spring 12 by the engagement of said lateral projections 21 with the face of said bracket. Means may be provided to prevent the trip-rod from being accidentally or maliciously removed from said slot, said means being shown as a wire passed through an eye or staple on the bracket 22, around the trip-rod, and having its ends fastened together, as by a padlock, which wire will be broken when the end 27 of the trip is depressed by a passing train. The rod is continued beyond said lug 20, as shown at 24, and is adapted to be struck by the trip, now to be described.

The trip consists in this form of my invention of a pivoted bar extending upward, as shown at 26, at an acute angle with the horizontal in the direction from which the locomotive adapted to coöperate therewith to throw the switch will approach, and has, further, beyond said upwardly-inclined portion a downwardly-extending projection 27, which normally lies immediately above the end 24 of the trip-rod. The other end of said trip-bar beyond its pivot carries or is formed into a counterweight 28, which tends to keep the inclined portion 26 of said bar elevated above the top of the adjacent rail. In the other end of the cylinder 7 from the head 6 of the rod 5 are slidably mounted the heads 30 and 43 of the rod 31, which is free to slide in said head within limits—viz., the pins 32 and 44, on the one hand, and the spring 33 on the other. The rod 31 is connected to the switch-lever 34, which may be any one of the ordinary and well-known forms. An internal flange 45 in the cylinder 7 engages the head 30 on the opposite side from the spring 33. This spring 33 must be stronger than the spring 12 and should be of such strength that it will not yield when the switch-lever is thrown to pull the switch-rod over to close the switch, so that to all intents and purposes the connection between the switch-lever and the cylinder 7 is a rigid one for the operation of ordinary switching. The purpose of the spring 33 is to permit the switch to yield when it is improperly set and

a train passes through it from the heel or rear side. The spring 33 can be omitted if the switch - lever mechanism is provided with springs, as in the well-known type of switch known as the "Ramapo" switch.

The means carried by the locomotive which coöperates with the trip preferably consists of a wheel 35, normally projecting laterally, (see Fig. 5,) but capable of being drawn in between the wheels 36 of the forward truck. The wheel 35 is held a short distance above the level of the top of the rail, as shown, the trip being arranged to project above the rail, as previously stated. Any suitable mechanism may be provided which will enable the engineer from his cab to withdraw the wheel 35, that illustrated consisting of a bell-crank lever 36, one end of which is connected by a pin and slot to the shaft 37 of the wheel 35 and the other end to a rod 38, leading by suitable connections to the engine-cab. The lever 36 and the shaft 37 are supported in hangers 39 and 40, respectively, and said shaft is provided with a collar 41, between which and the hanger 40 a coil-spring 42 is placed, which normally holds the wheel in operative position.

Before explaining the mechanism for moving the trip to inoperative position the operation of the parts so far described will now be stated. Assuming that the switch has been left open—i. e., in the position of Fig. 1—and that a main-line train is approaching from the left in said figure, the wheel 35 will strike the trip 25 unless the train is to run onto the siding, in which case the engineer will withdraw said wheel. The trip 25, striking the end 24 of the trip-rod 19, will release it from engagement with the bracket 22, and consequently dog 15, latch 18, and lever 17 will swing on their respective pivots, spring 12 will expand, and switch-rod 5 will be moved to close the switch. This of course leaves the switch-lever 34 set for the siding, and in pulling it over so that it will correspond in position to the switch the spring 12 is recompressed and the parts can be reset by engaging trip-rod 19 in the slot 23 again. When so set, the switch-rod and switch-lever are rigidly connected, so that the switch can be thrown open and closed again in the usual way, without affecting the automatic mechanism, the spring 33 being sufficiently resistant, as above stated, so that it does not yield at all when the rod 31 is pulled by the lever 34 to close the switch. Should, however, a train pass through the open switch from the rear, the effect in this form of my invention will be as follows: Rod 5 will be forced over toward the lever 34, and by reason of the engagement of pin 14 with lever 17, which engagement is maintained by latch 18 and dog 15, moves the cylinder 7 likewise toward the lever. Rod 31 remains stationary, and consequently, also, the head 43, while the head 30 moves with the cylinder by reason of its engagement

with the internal flange 45 thereof. The spring 33 is thus compressed and by its expansion resets the switch. Suppose now the switch to be closed to the main line and a train 5 to run from the siding onto the main line. The effect will be to move the rod 5 away from the lever 34, carrying the cylinder with it by reason of the engagement of stop 13 with head 8 and compressing spring 33 between head 43, 10 which moves with the cylinder and head 30, which remains stationary with rod 31. The switch will therefore remain closed after the passage of the train.

It is an infrequent occurrence that the switch 15 is left open when a train is due to pass on the main line, and therefore it is desirable that the trip be in operative position only when the switch has been inadvertently left open, and with that object in view I have provided 20 means connecting the trip to the switch-rod 5, so that the former will always be in inoperative position when the switch is closed. Such means may vary in detail, that shown in Fig. 1 comprising a lever 46, pivoted at 25 47 to the rod 5 and pivotally engaging at its free end with the crank 48 of the shaft 49, which extends alongside the other rail of the main line from that alongside which the trip-rod 19 extends. Said shaft 49 carries a 30 crank 50 at its other end, to which is pivoted a lever 51, connected by a swivel-collar 52, to which said lever 51 is pivoted, to one end of the rod 53, extending under the track and carrying at its other end the trip 25. A pin 54 35 on said rod engages the inclined surfaces of bolts 55, attached to the rail, so that as said rod is reciprocated it is also partially rotated. The trip 25 is loosely mounted on said rod, which is provided with stops 56, adapted to 40 engage a lug 57 on the trip to limit the movement of the latter. It will now be seen that whenever the switch-rod 5 is moved to close the switch the rod 53 will be also moved in a parallel direction, and thereby carry the trip 45 laterally away from the rail, so that its end 27 will no longer be above the end 24 of the trip-rod. Further, the rotation of said rod 53 by reason of the engagement of its pin 54 with the cams 55 will lower the trip, so that its 50 inclined portion 26 no longer projects above the rail.

Having thus described one form of mechanism in which my invention may be embodied and not restricting myself to the precise form or dimensions shown, since it is obvious various changes and modifications might be made therein without departing from the principles of my invention, what I claim is—

60 1. The combination with a railway-switch, of automatic means adapted and arranged to be operated by a train to close the same, and means to normally maintain said automatic means inoperative so that the ordinary operation of switching can be carried on as usual.

2. The combination with a railway-switch, and means whereby the same may be operated manually as usual, of a spring adapted and arranged to close the switch independently of said means, a device to normally maintain 70 said spring inoperative, means adapted and arranged to be struck by an approaching train to release said device, and means whereby the open switch can yield without releasing said device when a train runs through it 75 from the heel, substantially as set forth.

3. A railway-switch provided with means whereby it may be manually opened and closed as usual, in combination with a spring arranged to be released by a train to close the 80 switch, if the same has been wrongfully left open, and means whereby the switch can yield in either direction without releasing said spring when a train runs through it from the heel, substantially as set forth. 85

4. The combination with a railway-switch, of automatic mechanism adapted and arranged to be operated by a train to close the same, and means whereby the switch can yield in either direction without setting off the automatic mechanism when a train runs through it from the heel, substantially as set forth. 90

5. In a railway-switch, the combination with a switch-rod and a switch-lever, of means normally connecting said rod and lever, whereby the switch may be manually thrown in either direction in the ordinary way, of a spring adapted and arranged to move said rod relatively to said lever in a direction to close the switch when the connection between said rod and lever is broken, and means adapted and arranged to be operated by an approaching train to break said connection and cause said spring to act to close the switch, substantially as set forth. 95

6. In a railway-switch, the combination with a switch-rod and a switch-lever, of a spring adapted and arranged to move said rod relatively to said lever in a direction to close the switch, a latch device adapted and arranged to connect said switch rod and lever and maintain said spring energized whereby the switch can be positively thrown in either direction by means of the lever, means to normally hold said latch device in operative position, and a trip adapted and arranged to be actuated by an approaching train to release said means and thereby permit said spring to act to close the switch, substantially as set forth. 100 105 110 115

7. In a railway-switch, the combination with a switch-rod and a switch-lever, of a spring adapted and arranged to move said rod relatively to said lever in a direction to close the switch, means to normally hold said rod 120 and lever connected against the force of the spring so that the switch may be thrown manually in either direction in the ordinary way, of a trip-rod connected to said means and extending alongside the track, means to hold 125 130

- said trip-rod against longitudinal movement and thereby maintain the connection between said switch rod and lever, and a trip adapted and arranged to be operated by a train approaching the switch to release said trip-rod and thereby break the connection between said switch rod and lever and permit said spring to act to close the switch, substantially as set forth.
8. In a railway-switch, the combination with a switch-rod and a switch-lever, of a cylinder connected to said lever and in which said rod is slidably mounted, a spring interposed between said rod and said cylinder and adapted to move said rod relatively to said cylinder in a direction to close the switch, a latch pivoted to said cylinder and adapted to engage a projection on said switch-rod to hold the same against movement by said spring, means to normally hold said latch in engagement with said projection and a trip adapted and arranged to be operated by a train approaching the switch to release said latch and permit said spring to act to close the switch, substantially as set forth.
9. In a railway-switch, the combination with a switch-rod and a switch-lever, of a cylinder connected to said lever and in which said rod is slidably mounted, a spring interposed between said rod and cylinder and adapted to move said rod relatively to said cylinder in a direction to close the switch, a latch pivoted to said cylinder and adapted to engage a projection on said switch-rod to hold the same against movement by said spring, a trip-rod connected to said latch and extending alongside the track, means to hold said rod against longitudinal movement and thereby maintain said latch in engagement with said projection, whereby said spring is energized, and a trip adapted and arranged to be actuated by a train approaching the switch, to release said trip-rod from said holding means, whereby said latch is released and the switch is moved by said spring to close the switch, substantially as set forth.
10. In a railway-switch, the combination with a switch-rod having a head on its free end, of a cylinder in one end of which the head of said rod is slidably mounted, a switch-lever connected to the other end of said cylinder, a spring interposed between said head and the cylinder, and adapted to move said rod in said cylinder to close the switch, a pivoted latch carried by said cylinder and a projection on said rod with which said latch is adapted to engage to hold said rod against movement by said spring, a trip-rod connected to said latch and extending alongside the track, means to normally hold said trip-rod in position to keep said latch and projection in engagement, and a trip adapted and arranged to be actuated by an approaching train to release said trip-rod and latch and thereby permit said spring to act to close the switch, substantially as set forth.
11. In a railway-switch, the combination of a switch-rod, a switch-lever and a latch device to normally connect the same, a spring adapted and arranged to move said switch-rod relatively to said lever to close the switch when said latch device is released, a trip-rod extending alongside the track and connected to said latch device, a stationary bracket having a vertical slot therein open at the lower end and through which said trip-rod is adapted to pass, means on said trip-rod to engage one face of said bracket when said trip-rod is in said slot whereby said trip-rod is held against longitudinal movement and said latch device is held in position to connect said switch rod and lever, a trip normally supported above the end of said trip-rod adjacent to said bracket, said trip being adapted and arranged to be operated by a train approaching the switch to drive said trip-rod out of said slot, release said latch device and permit said spring to act to close the switch.
12. In a railway-switch, the combination with a switch-rod having a head on its free end, of a cylinder in one end of which said head is slidably mounted, a switch-lever connected to the other end of said cylinder a spring interposed between said head and said cylinder and adapted to move said rod in said cylinder in a direction to close the switch, a latch pivoted on said cylinder, a projection on said rod with which said latch is adapted to engage to hold said rod against movement by said spring, a dog pivoted to said rod and adapted to engage said latch to hold the same in engagement with said projection, a trip-rod pivoted to said dog and extending alongside the track, a stationary bracket having a slot therein open at the lower end and through which said trip-rod is adapted to pass, means on said trip-rod adapted to engage the face of said bracket, when said trip-rod is in said slot, and to prevent longitudinal movement of said rod, whereby said dog and latch and said latch and projection are held in engagement, respectively, a trip normally supported above the end of said trip-rod adjacent to said bracket, and adapted and arranged to be depressed by a train approaching the switch, to drive said trip-rod out of said slot, whereby said dog releases said latch and said spring is permitted to act to move the switch-rod and close the switch, substantially as set forth.
13. A railway-switch rod provided with means whereby it may be manually shifted in either direction in the usual way, in combination with a spring arranged to move said rod in one direction independently of said manual means, means to hold said rod against movement by said spring, a trip arranged to be struck by a train to release said rod from said holding means, and connections between

said rod and said trip whereby the latter will be moved to an inoperative position whenever said rod is shifted in one direction by said manual means, substantially as set forth.

- 5 14. The combination with a railway-switch provided with means whereby it may be manually operated in the usual way, of a spring arranged to close said switch independently of said manual means, means to normally prevent the operation of said spring, a trip arranged to be struck by a train to release said spring and connections between said switch and said trip whereby the latter will be moved to an inoperative position when the switch is closed by said manual means, substantially as set forth.
- 10
- 15

15. In a railway-switch, the combination of a switch-rod and a switch-lever, of a spring adapted and arranged to move said rod relatively to said lever in a direction to close the switch, means to normally hold said rod and lever connected against the force of said spring so that the switch may be thrown manually in either direction in the usual way, a trip 20 adapted and arranged to be operated by a train approaching the switch to break the connection between said rod and lever and permit said spring to act to close the switch, a support for said trip mounted to reciprocate 25 in a direction substantially parallel to the movement of said switch-rod and connections between said support and said switch-rod whereby when the switch is closed the trip is moved to inoperative position, substantially 30 as set forth.

16. In a railway-switch, the combination of a switch-rod and a switch-lever, of a spring adapted and arranged to move said rod relatively to said lever in a direction to close the switch, means to normally hold said rod and lever connected against the force of said spring so that the switch may be thrown manually in either direction in the usual way, a bar mounted to slide parallel to said switch-rod, a trip pivoted to one end of said bar and arranged to be struck by a train approaching the switch when the latter is open and thereby break the connection between said switch rod and lever and permit said spring to act to close the switch, connections between said switch-rod and said bar whereby they move synchronously and means to partially rotate said bar during such movement, whereby when the switch is closed the trip will be moved laterally and depressed substantially as and for the purpose set forth

17. In a railway-switch, the combination of a switch-rod and a switch-lever, a latch device to normally connect said rod and lever so that 60 the switch can be thrown normally in either direction in the usual way, a spring adapted and arranged to move said rod relatively to said lever in a direction to close the switch when the connection between said rod and le-

ver is broken, a trip-rod connected to said 65
latch device and extending alongside the track,
means to normally hold said rod against lon-
gitudinal movement, a bar slidably mounted
parallel to said switch-rod, a trip pivotally
carried by said bar and adapted and arranged 70
to be actuated by a train approaching the
switch when the latter is open to release said
trip-rod and thereby disengage said latch de-
vice and permit said spring to act to close the
switch, connections between said switch-rod 75
and said bar whereby the latter will move
said trip laterally away from said trip-rod
when the switch is closed, and means to simul-
taneously rotate said bar during such move-
ment whereby said trip will also be depressed 80
out of position to be actuated by the train,
substantially as set forth.

18. In a railway-switch, the combination of a switch-rod and a switch-lever, a cylinder to which said lever is connected and in which one end of said rod is slidably mounted, a spring in said cylinder adapted and arranged to move said rod relatively to said lever in a direction to close the switch, a latch device carried by said cylinder and adapted to hold said rod against movement by said spring, a bar mounted to reciprocate in a direction parallel to the movement of said switch-rod, a trip pivotally carried on one end of said bar and adapted to be struck by a train approaching the switch when the latter is open, means arranged to be operated by said trip to release said latch device and permit said spring to close the switch, a lever carried by the other end of said switch-rod, a lever swiveled to the other end of said bar, a shaft having a crank on each end engaging said levers respectively, whereby said bar will be reciprocated synchronously with said switch-rod, a projection on said bar and stationary cam devices adapted and arranged to engage said projection and partially rotate said bar during such reciprocatory movement, whereby when the switch is closed said trip will be removed out of position to engage said latch-releasing means and whereby said trip will also be depressed out of position to be engaged by the train, substantially as set forth. 185 90 95 100 105 110

19. In a railway-switch, the combination with a switch-rod and a switch-lever normally connected so that switching can be carried on in the usual way, of means whereby the connection between said rod and lever may be broken and the open switch be automatically closed, by a train approaching said switch on the point side, means whereby said rod can move relatively to said lever without breaking the connection between said rod and lever when the switch-rails are cammed in either direction by the wheels of a train running through it from the heel side, substantially as set forth. 115 120 125

20. In a railway-switch, the combination

with a switch-rod and a switch-lever, a latch device to hold said rod and lever normally connected, whereby switching can be carried on in the usual way, a spring adapted and arranged to move said rod relatively to said lever when said latch device is released, a trip adapted and arranged to be actuated by an approaching train to release said latch device and permit said spring to act to throw the switch, a second spring interposed between said rod and lever of sufficient strength so as not to yield in the ordinary operation of switching, but which will yield to permit said rod to move relatively to said lever when the switch-rails are cammed over by the wheels of a train passing through it from the heel side, substantially as set forth.

21. In a railway-switch, the combination with a switch-rod, of a cylinder surrounding the free end of said rod, a spring adapted and arranged to force said rod into said cylinder, a stop to limit the withdrawal of said rod from said cylinder a switch-lever, a bar connected thereto and having its free end within said cylinder, two collars slidably mounted on said bar within said cylinder, a coil-spring interposed between said collars, stops on said bar to limit the movement of said collars by said spring, an internal flange on said cylinder engaging the innermost of said collars on its side nearest the end of said bar, a latch device carried on said cylinder and adapted to engage said switch-rod to prevent relative movement between said rod and cylinder, a trip - rod adapted to normally maintain said latch device in operative position, and a trip adapted and arranged to be operated by an approaching train to release said trip-rod, disengage said latch and permit said switch-rod to move to throw the switch, said coil-spring being adapted to yield only when the switch-rails are cammed over by a train passing the incorrectly-set switch from the heel side thereof, substantially as set forth.

45 22. In a railway-switch, the combination of

a switch-rod having a head on its free end, a cylinder in one end of which said head is slidably mounted, a spring interposed between said head and the adjacent end of the cylinder, a stop on said rod engaging said end of the cylinder and limiting the outward movement of said rod from said cylinder, a switch-lever, a bar connected thereto at one end and having its other end within said cylinder, two collars slidably mounted on said bar within said cylinder, a coil-spring interposed between said collars, stops on said bar to limit the movement of said collars by said spring, an internal flange on said cylinder engaging that one of said collars nearest the end of said bar and on the side of said collar nearest that end, a latch pivoted on said cylinder, a lever also pivoted on said cylinder and adapted to be engaged by one arm of said latch, a projection on said switch-rod, adapted to be engaged by said lever, a dog pivoted to said switch-rod and adapted to engage the other arm of said latch, means to normally hold said parts engaged and means adapted and arranged to be operated by a train approaching the switch to release said holding means, whereby the switch rod and lever are normally connected so that switching may be performed in the usual way, whereby the switch will be automatically closed by an approaching train on the main track if inadvertently left open, and whereby the switch-rod and cylinder can move relatively to the switch-lever and its connecting-bar when the switch has been incorrectly set and a train runs through it from the heel, whether it were set for the main line or the siding, substantially as set forth.

In testimony whereof I have signed my name to this specification in the presence of two subscribing witnesses.
